UNITED STATES PATENT OFFICE.

J. N. BODINE, OF BRIDGETON, NEW JERSEY.

IMPROVEMENT IN BOTTLES.

Specification forming part of Letters Patent No. **29,563**, dated August 14, 1860.

To all whom it may concern:

Be it known that I, J. N. BODINE, of Bridgeton, county of Cumberland, State of New Jersey, have invented certain new and useful Improvements in Bottles, of which the following is a full, clear, and exact description, reference being had to the accompanying drawings, forming part of this specification, in which—

Figure 1 represents a perspective view of a bottle embracing my improvements. Fig. 2 represents a plan of the top of the neck; and Fig. 3 represents a perspective view of the upper part of the bottle, with a portion of the neck removed.

My improvement in bottles is more especially adapted to those used for liquids highly impregnated with gases, which, when bottled, exert a powerful force on the cork and tend to throw it out of the neck of the bottle, which renders it necessary to confine the cork by means of cords, wire, or some description of strap in order to retain it in the bottle.

Among other modes proposed to retain the cork in bottles used for bottling these liquids is to form two vertical grooves on the interior of the neck, opposite each other, and leading into a curved recess a short distance below the top of the neck, extending entirely around the interior of the neck of the bottle. With the bottle thus made a metallic stopper only is used, the lower end of which (that part extending below the curved recess) is surrounded with cork or some elastic packing to make the stopper tight in the bottle, and the upper part provided with two projecting ears or wings, which enter the side grooves when the stopper is driven into the bottle and pass to the curved recess below. The stopper is then turned so that these wings pass to one side of the groove and enter the curved recess, which prevents the cork from being forced out by the pressure of the fluid within. The objection to bottles thus constructed is that they can only be used with this peculiar description of stopper, as the ordinary cork, when driven into the neck of this bottle, is caused by the pressure of the liquid to expand and fill the horizontal groove, which renders it difficult to withdraw without breaking, so that the same cork can rarely be used more than once.

The object of my improvement is to remedy this defect, and so construct the bottle that an ordinary cork may be used and held securely

without the application of external fastenings; and my invention for effecting this object consists in forming on the interior of the neck of the bottle, and on opposite sides, vertical grooves in connection with horizontal grooves extending laterally on either side from the bottom of the vertical grooves, for the purpose of receiving a small independent block or wedge of wood or other material, which, after the bottle is corked, is driven into the vertical groove and slid around into the horizontal, and thus prevents the cork from being forced out by the pressure of the liquid within.

In the accompanying drawings is represented a bottle embracing my improvements, which is made in any of the well-known forms in common use. The neck of the bottle is blown with a vertical groove, *a*, on the interior, extending from the top down a short distance, and leading from the bottom of this groove, either to the right or left, is a narrow groove, *b*, which may extend, if thought best, entirely around the neck. The mouth of the bottle is closed with an ordinary cork, *A*, which, after being driven into the bottle, is confined by small plugs or wedges *c* of wood or other material, whose thickness is little greater than the depth of the groove. This plug is driven into the vertical groove to its bottom and alongside of the cork, and then turned into the horizontal groove, and is retained in place by the elasticity of the cork and the pressure of the gas or liquid in the bottle upon the cork, which causes it to recede and brings the wedge tightly against the upper wall of the groove, and thus prevents the cork from being forced out by the pressure of the liquid. In opening the bottle this wedge is drawn back by an instrument made for that purpose until opposite the vertical groove, when the cork flies easily by the pressure of the gas, or may be withdrawn, if necessary, in the usual manner without injury.

The advantages of this construction of bottle and mode for retaining the cork in the bottle are that the cork is fastened with much greater facility than by the devices heretofore used; that this fastening is much less expensive; that the cork flies readily on drawing back the plugs opposite the vertical grooves, and also that the cork is uninjured by this fastening and may be used several times.

It will be seen from the small dimensions of

the horizontal grooves, and from their being almost filled by the fastening-wedge, that there is little or no cavity left in which the cork expands, preventing its withdrawal with ease, as is the case with those bottles made with the large curved recess below the vertical groove.

Having thus described my improvement in bottles and in the mode of fastening the cork, what I claim as new, and desire to secure by Letters Patent, is—

1. A bottle constructed with vertical and short horizontal grooves on the interior of the

neck, substantially as described, for the purpose set forth.

2. The method of fastening the cork in the bottle by means of vertical and horizontal grooves, in combination with an independent plug or block.

In testimony whereof I have subscribed my name.

J. N. BODINE.
